SUPPORTING STAND FOR A DOMESTIC ICE CRUSHER

Joseph Palma, Jr., Chicago, Ill., assignor, by mesne assignments, to The Dazey Corporation, St. Louis, Mo., a corporation of Missouri

Application June 23, 1954, Serial No. 31,129

Term of patent 14 years

(Cl. D89—1)

FIG. 1.

FIG. 2.

FIG. 4.

FIG. 3.

Fig. 1 is a perspective view of the supporting stand for a domestic ice crusher;

Fig. 2 is a top plan view thereof;

Fig. 3 is a side elevational view thereof, and

Fig. 4 is a front elevational view thereof.

The ice crusher shown in broken lines is for the purpose of illustration.

I claim:

The ornamental design for a supporting stand for a domestic ice crusher, substantially as shown and described.
